1**2,806,417****MANHOLE VENTILATOR**

Clarence J. Carroll, Carlinville, Ill.

Application August 10, 1955, Serial No. 527,581

3 Claims. (Cl. 98—1)

The present invention relates to new and useful improvements in ventilators of a type designed particularly for use in a manhole for ventilating underground tunnels or passages.

An important object of the invention is to provide a ventilator embodying a plurality of vanes supported on a vertical shaft in a position to project partly above and partly below the manhole to deflect wind currents downwardly into the tunnel or passage.

Another object of the invention is to provide means for easily and quickly adjusting the direction of the vanes in accordance with the direction of the wind.

A still further object is to provide a collapsible ventilator of this character.

An additional object is to provide a device of this character of simple and practical construction, which is efficient and reliable in operation, relatively inexpensive to manufacture, easy to set up in operative position in a manhole and which is otherwise well adapted for the purpose for which the same is intended.

These, together with other objects and advantages which will become subsequently apparent, reside in the details of construction and operation as more fully hereinafter described and claimed, reference being had to the accompanying drawings forming a part hereof, wherein like numerals refer to like parts throughout, and in which:

Figure 1 is a perspective view;

Figure 2 is an enlarged transverse sectional view taken on the line 2—2 of Figure 1;

Figure 3 is a vertical sectional view taken on the line 3—3 of Figure 2;

Figure 4 is a transverse sectional view taken on the line 4—4 of Figure 3; and

Figure 5 is a perspective view of the locking collar for the vanes.

Referring now to the drawings in detail, wherein, for the purpose of illustration, I have disclosed a preferred embodiment of the invention, the numeral 5 designates a shaft which is threaded at each end, and the shaft is suspended in a vertical position in a manhole 6 by extending the upper end of the shaft through an opening 7 in a cross-bar 8 and with a wing nut 9 threaded on the upper end of the shaft to support the shaft below the cross-bar. The cross-bar 8 is placed on top of the side rails 10 of a conventional type of manhole guard designated generally at 11 and the cross-bar 8, with the shaft 5 suspended therefrom, is placed in a position on the guard 11 so that the lower end of the shaft extends downwardly partly into the tunnel or passageway 12 for which the manhole is provided.

2

A plurality of vanes 13 of substantially rectangular shape are formed at one longitudinal edge with bearings 14 in which the shaft 5 is positioned to rotate or turn the vanes thereon. A wing nut 15 is threaded on the lower end of shaft 5 to support the vanes on the lower portion of the shaft and with the lower ends of the vanes extending downwardly into the manhole 6.

The vanes 13 are locked in a predetermined angularly related position with respect to each other on the shaft, 10 preferably at angles of 90°, as shown in Figure 4 of the drawings, by means of a locking collar 16 rotatably and slidably mounted on the shaft and having downwardly projecting teeth 17 at its underside with which the upper edges of the vanes 13 are engaged for locking engagement therewith.

A sleeve 18 extends upwardly from collar 16 and over which the lower end of a coil spring 19 is inserted to rest on top of the collar 16. The upper end of the spring 19 bears against the underside of the cross-bar 8 and is tensionally adjusted by the upper wing nut 9 to hold the collar 16 lockably engaged with the wing.

A stop pin 20 is inserted transversely through shaft 5 under the locking collar 16 and above the vanes 13 to limit downward movement of the stop collar on the shaft 20 by the spring and to hold the locking collar on the upper portion of the shaft while the vanes are being mounted or rotatably adjusted on the lower portion thereof.

In the operation of the device, the vanes 13, locking collar 16, and spring 19 are assembled on the shaft 5 and attached to the cross-bar 8 in the manner illustrated in Figures 1 and 3 of the drawing. The cross-bar 8 is then placed on the upper rails 10 of the manhole guard 11 to support the lower portion of the vanes in the manhole 6. The vanes 13 are turned in a direction to deflect wind currents downwardly through the manhole into the tunnel or passage thereunder to provide ventilation therefor.

The vanes 13 are adjusted in accordance with the direction of the wind, from a position below the vanes, by 30 loosening the lower wing nuts 15 and dropping the vanes 13 downwardly on the shaft sufficiently to free the upper edges of the vanes from the locking collar 16 and the vanes may then be turned in the desired direction and again lockably engaged with the locking collar 16 by 40 tightening the lower wing nut 50.

The vanes 13, locking collar 16 and spring 19 may be easily and quickly removed from the shaft, as well as from the cross-bar 8 for conveniently carrying or storing the ventilator.

50 The foregoing is considered as illustrative only of the principles of the invention. Further, since numerous modifications and changes will readily occur to those skilled in the art, it is not desired to limit the invention to the exact construction and operation shown and described, 55 and accordingly all suitable modifications and equivalents may be resorted to, falling within the scope of the invention as claimed.

What is claimed as new is as follows:

60 1. A ventilator for a manhole of an underground passage comprising in combination, a vertical stationary shaft, a plurality of vanes slidably and swingably supported in a radial projecting position on the shaft, means carried by the shaft above the vanes for locking the vanes in swingably adjusted position, means at the upper end 65 of the shaft supporting the vanes in a position partly above

and partly below a manhole, and means at the lower end of the shaft supporting the vanes in engagement with the locking means and adapted for releasing from a position in an underground passage below the vanes to adjust the vanes on the shaft.

2. The combination of claim 1, said first named means comprising a member interlocking with said vanes and slideable on the shaft out of interlocking position to permit swingable adjustment of the vanes.

3. The combination of claim 1, said second named means comprising a horizontal bar suspending said shaft, and supporting rails for said bar elevating the same.
